TENSION EQUALIZING DEVICE

Albert Johnson, New York, N. Y.

Application August 4, 1945, Serial No. 608,981

4 Claims. (CL 242—156)

1

This invention is for a device for equalizing the tension on a strand of wire, thread and the like as the same is unwound from a spool or reel.

In removing or unwinding a strand from a spool or reel, the tension or pull on the strand to effect rotation of the spool or reel increases as the quantity of material thereon decreases or in other words as the radius of the "take-off" decreases. Unless provision is made for equalizing the tension on the strand, the same is gradually wound tighter on the receiving spool or form as the tension increases. In order to overcome this objection, the present invention provides a device by which the spool or reel is subjected to a braking action in relation to the quantity or weight of the material thereon whereby substantially the same tension or pull on the strand is required to effect rotation or turning of the spool or reel irrespective of the quantity of material thereon.

The invention further provides a device of the indicated character in which the spool or reel is supported upon rockable braking shoes having resilient movement at the free end of a rock arm.

The invention also has for an object the provision of a spool or reel tensioning device mounted on a reciprocating support which is tensioned against movement in the direction of the pull on the strand whereby the tension thereon may be visually determined and which functions to take up any sudden increase in tension on the strand due to catching of the same on the winding on the spool or reel to thereby eliminate possible breaking of the strand.

The invention also has in view the provision of means for resiliently suspending a spool or reel of excessive weight while supported upon brake shoes having resilient upward movement so as to prevent undue tension on the strand for rotating the same to effect unwinding thereof.

With the foregoing and other objects in view reference is now made to the following specification and accompanying drawings in which the preferred embodiment of the invention is illustrated.

In the drawings:

Fig. 1 is a side view of a tension equalizing device constructed in accordance with the invention.

Fig. 2 is an end view thereof.

Fig. 3 is an enlarged fragmentary view taken approximately on line 3—3 of Fig. 2.

Fig. 4 is a fragmentary vertical sectional view taken approximately on line 4—4 of Fig. 1.

2

Fig. 5 is a fragmentary longitudinal sectional view taken on line 5—5 of Fig. 4.

Referring to the drawings by characters of reference, the tension equalizing device includes a base 10 provided with longitudinally extending side rails 11 secured to opposite longitudinal side edges and projecting upwardly above the upper surface thereof to define guides between which is mounted a reciprocating support or plate 12. The base 10 is formed with a rectangular shaped opening 13 extending vertically therethrough in which openings are mounted a plurality of longitudinally spaced pairs of rollers 14 carried by cross shafts 15 journaled at their opposite ends in the opposite walls of the base which define the opening 13. The rollers 14 support the plate 12 for reciprocating movement thereon longitudinally of the base 10.

The plate 12 has mounted thereon at one end 20 thereof a pair of laterally spaced standards 16 each of which is formed with a vertical slot 17 extending downwardly from the upper end to a point adjacent the bottom thereof and which slots open through the opposite side faces of the standards to dispose the same in transverse alignment. A spool or reel A mounted on a cross shaft 18 is adapted to be disposed between the standards with the shaft 18 mounted for rotation in the slots 17.

In order to provide means for equalizing the tension or pull on the "take-off" strand of the material wound on the spool or reel A, a pair of brake shoes 19 journaled on a cross shaft 20 is provided which engage the peripheries of the flanges of the spool or reel A vertically below the center thereof. The cross shaft 20 is secured in a support 21 located at the free end of a lever 22 pivoted intermediate its length to a yoke 23, the yoke being secured to the support or plate 12 with the opposite end of the lever extending upwardly and connected with the support or plate 12 by a coiled contractile spring 24. The spring 24 tensions the brake shoes 19 against downward movement so that the same resiliently

40 supports the spool or reel A and provides means whereby the spool or reel has vertical reciprocating movement with the slots 16 serving as guides for the reciprocating as well as rotary movement thereof. Thusly supported, a frictional braking action against rotation of the spool or reel will be set up between the flanges thereof and the brake shoes in relation to the combined weight of the spool or reel and the material wound thereon. Since the frictional braking action of 45 the spool or reel decreases with the removal or

unwinding of the material therefrom and the radius of the "take-off" also decreases with the removal or unwinding of the material, the strand being unwound therefrom will be under substantially the same tension or pull to effect rotation of the spool or reel irrespective of the amount of material thereon.

This permits of the winding of the strand indicated by the reference character B on a spool or form C directly from the spool or reel A and since the tension on the strand B is substantially the same during the unwinding thereof from the spool or reel A the strand will be wound on the spool or form C with the same degree of tightness.

The support or plate 12 is provided with a longitudinally extending inverted T shaped slot 25 opening through the upper and lower faces thereof for slidably receiving therein a bolt 26 extending upwardly through the base of the yoke 23 and which is adapted to be disposed at longitudinally spaced positions for adjustably fulcruming the lever 22 in anyone of the openings 27 therein to thereby vary the distance of the cross shaft 20 from the said fulcrum and the tension of the spring 24 against downward movement of the brake shoes 19.

In order to reduce the braking action of the brake shoes against a heavy spool or reel a pair of coiled expansion springs 28 is provided which are respectively secured at their upper ends to tubular adjusting screws 29 and at their lower ends to rings 30 mounted on the protruding ends of the cross shaft 18 between a fixed collar 31 and a retaining nut 32 threadedly engaging each end of the shaft. The adjusting screws 29 extend through openings in the cross head 33 secured upon the upper ends of the standards 16, the protruding ends of the screws being engaged by nuts 34 for adjusting the upward pull or tension of the springs 28 whereby the spool or reel A is suspended between the rings 30 for vertical reciprocating and rotary movements with the weight thereof disposed upon the brake shoes 19 in accordance with the setting of the nuts 34. Secured to the rings 30 are rods 35 extending upwardly within the springs 28 with the upper free ends of the rods slidably disposed in the bores of the adjusting screws 29 respectively and which function to prevent rotation of the rings 30 and retain the springs 28 in vertical alignment with the rings and adjusting screws.

The rearmost furcation 36 of each of the standards 16 is formed with an upper portion 37 hingedly connected therewith by hinge 38 to permit of the outward swinging of the upper portions 37 so that the reel or spool A may be removably disposed between the standards 16 with the cross shaft 18 located in the slots 17. The upper ends of the upper portions of the furcations 36 are beveled as at 39 providing a clearance between the same and the cross head 33 to permit of the outward swinging of the said portions 37. Bolts 40 extend through the said upper portions 37 and the opposite furcations of the standards 16 securing the said upper portions against stops 41 depending from the under face of the cross head with the said upper portions in vertical alignment with the lower portions thereof and spaced from the opposite furcations by the slots 17.

The support or plate 12 is tensioned against movement in the direction of the pull on the strand B exerted thereon to effect rotation of the spool or reel A by means of a coiled contractile spring 41 secured at one end to the intermediate cross shaft 15 and at the opposite end to a

hook 42 secured to and depending from the under face of the said support or plate. The forward end of the said support or plate is provided with a pointer 43 projecting over the upper edge of the adjacent side rail 11 provided with a scale 44 on the upper edge thereof for visually indicating by the movement of the pointer 43 with the support or plate 12 the degree of tension exerted on the strand B when unwinding the same from the spool or reel A.

The lever 22 is connected with the spring 24 by a bolt 45 projecting upwardly through an opening in the end of said lever for varying the elevation of the brake shoes 19 by adjusting the nut 46 thereon.

In order to prevent binding of the forward portion of the brake shoes 19 on the flanges of the spool or reel A, the cross shaft 20 protrudes into the slots 17 and between the brake shoes and the standards 16 the cross shaft has secured thereon the enlarged lower ends of upwardly extending arms 46 having outwardly directed free ends 47 projecting into the slots 17 respectively. The brake shoes 19 may engage the peripheries of the flanges of the spool or reel A or the flanges may be formed as disks secured to the cross shaft 18 between which the material is wound on a spool in the form of a drum.

What is claimed is:

30. 1. In a device for equalizing the tension on a strand of material required to effect the unwinding thereof from a spool having a quantity of said material thereon and mounted on a cross shaft, a support, a pair of spaced standards affixed to said support and each formed with an upwardly extending slot opening through the opposite side faces thereof to dispose the slots in transverse alignment with each other for guidedly receiving therein the said cross shaft for reciprocatory and rotary movements with the spool arranged between the standards, a lever pivoted intermediate its length upon said support to dispose the opposite ends thereof for vertical swinging movement, a cross shaft secured to one end of said lever, a brake shoe rockably mounted on said cross shaft on each side of said lever upon which the spool is supported and frictionally engages when rotated to effect unwinding of the strand, a coiled contractile spring connected between the opposite end of said lever and the support for resiliently supporting upon said brake shoes the weight of the spool and material wound thereon, a longitudinally extending base for said support, means mounting said support for longitudinal reciprocatory movement thereon and a coiled contractile spring connected with said base and said support for tensioning the support against the tension on the strand required to effect unwinding thereof from the spool.
35. 2. In a device for equalizing the tension on a strand of material required to effect the unwinding thereof from a spool having a quantity of said material thereon and mounted on a cross shaft, a longitudinally extending support, a pair of spaced standards affixed to said support at one end thereof and each formed with an upwardly extending slot opening through the opposite side faces thereof to dispose the slots in transverse alignment with each other for guidedly receiving therein the said cross shaft for reciprocatory and rotary movements with the spool arranged between the standards, a lever, means pivoting said lever intermediate its length upon said support to dispose the opposite ends thereof for ver-

tical swinging movement, a cross shaft secured to one end of said lever, a brake shoe rockably mounted on said cross shaft on each side of said lever upon which the spool is supported and frictionally engages when the spool is rotated to effect unwinding of the strand, a coiled contractile spring connected between the opposite end of said lever and the support for resiliently supporting upon said brake shoes the weight of the spool and material wound thereon, said means being adjustable longitudinally of the support for varying the pivotal connection with the lever and thereby varying the tension of said spring against the spool, a longitudinally extending base, a plurality of rollers mounted on said base on which the support is disposed for reciprocatory movement thereof longitudinally of said base and a coiled contractile spring connected with said base and said support for tensioning the support against the tension on the strand required to effect unwinding thereof from the spool for taking up any sudden increase in tension on the strand to prevent breakage thereof.

3. In a device for equalizing the tension on a strand of material required to effect the unwinding thereof from a spool having a quantity of said material thereon and mounted on a cross shaft, a support, a pair of spaced standards affixed to said support and each formed with an upwardly extending slot opening through the opposite side faces thereof to dispose the slots in transverse alignment with each other for guidedly receiving therein the said cross shaft for reciprocatory and rotary movements with the spool arranged between the standards, a ring mounted on each end of said cross shaft, adjusting screws carried by the upper ends of said standards respectively and coiled contractile springs connected between said adjusting screws and said rings providing an upward tension upon said cross shaft in opposition to the weight of said spool, a lever pivoted intermediate its length upon said support to dispose the opposite ends thereof for vertical swinging movement, a cross shaft secured to one end of said lever, a brake shoe rockably mounted on said cross shaft on

each side of said lever and frictionally engaging the spool when the same is rotated to effect unwinding of the strand, a coiled contractile spring connected between the opposite end of said lever and the support for resiliently urging the brake shoes into engagement with the spool and for supporting the spool by the brake shoes and the first named springs, a longitudinally extending base for said support, means mounting said support for longitudinal reciprocatory movement thereon, a coiled contractile spring connected with said base and said support for tensioning the support against the tension on the strand required to effect unwinding thereof from the spool to thereby take up a sudden increase in tension on the strand to prevent breaking thereof and a pointer and scale carried respectively by said support and base for visually indicating the tension on said strand.

4. In a device for equalizing the tension on a length of material required to effect the unwinding thereof from a roll mounted on a cross shaft, a support, a pair of spaced standards affixed to said support and each formed with an upwardly extending slot opening through the side faces thereof to dispose the slots in transverse alignment for guidedly receiving the cross shaft therein for reciprocatory and rotary movements with the roll arranged between the standards, a lever pivoted intermediate its length upon said support to dispose the opposite ends thereof for vertical swinging movement, a brake shoe rockably mounted on one end of said lever upon which the roll is supported and frictionally engages when rotated to effect unwinding of the length of material, means tensioning the opposite end of said lever for resiliently supporting upon said brake shoe the weight of the roll and material thereon, a longitudinally extending base for said support, means mounting said support for longitudinal reciprocatory movement thereon and tension means connected with said base and said support for tensioning the support against the tension on the length of material required to effect unwinding thereof from the roll.

ALBERT JOHNSON.
